(57) **CLAIM**

The ornamental design for a dual dampener apparatus, as shown and described.

DESCRIPTION

FIG. 1 is a perspective view of a dual dampener apparatus in accordance with my invention;

FIG. 2 is a front elevation view of the dual dampener apparatus shown in FIG. 1;

FIG. 3 is a back elevation view of the dual dampener apparatus shown in FIG. 1;

FIG. 4 is a side elevation view of the dual dampener apparatus shown in FIG. 1;

FIG. 5 is a side elevation view opposite the view shown in FIG. 4 of the dual dampener apparatus shown in FIG. 1;

FIG. 6 is a top plan view of the dual dampener apparatus shown in FIG. 1;

FIG. 7 is a bottom plan view of the dual dampener apparatus shown in FIG. 1; and,

FIG. 8 is a reverse perspective view of the dual dampener apparatus shown in FIG. 1.

The broken lines depict environmental subject matter only and form no part of the claimed design.
